UNITED STATES PATENT OFFICE.

CHARLES H. TURNER, OF WORCESTER, MASSACHUSETTS, ASSIGNOR TO OSGOOD
BRADLEY CAR COMPANY, OF WORCESTER, MASSACHUSETTS, A CORPORATION OF
MASSACHUSETTS.

CAR VENTILATOR.

Application filed August 13, 1921. Serial No. 492,044.

To all whom it may concern:

Be it known that I, CHARLES H. TURNER, a citizen of the United States, residing at Worcester, in the county of Worcester and 5 State of Massachusetts, have invented a new and useful Car Ventilator, of which the following is a specification.

This invention relates to a ventilator particularly designed for use in the upper part 10 of a railway passenger car. Much difficulty has been encountered in securing proper ventilation of such cars when in motion, as strong direct currents of air are objectionable and the exclusion of driving rain or 15 sleet is an absolute necessity.

It is the object of my invention to provide a car ventilator which combines simplicity of construction with reliable and satisfactory operation. With this general object in 20 view, my invention relates more particularly to arrangements and combinations of parts which will be hereinafter described and more particularly pointed out in the appended claims.

25 Two slightly different forms of my invention are shown in the drawings in which

Fig. 1 is a sectional elevation of my improved ventilator as applied to a car roof;

Fig. 2 is a partial plan view of the ventilator shown in Fig. 1;

Fig. 3 is a detail sectional view taken along the line 3—3 in Fig. 1;

Fig. 4 is a partial bottom view of the damper or air regulator shown in Fig. 1;

35 Fig. 5 is a sectional elevation of a slightly modified form of my improved ventilator, applied to a car of the monitor type, and

Fig. 6 is a side elevation of the ventilator shown in Fig. 5.

40 Referring to Figures 1 to 4, I have shown a ventilator of a substantially rectangular form, including an end 10, a grid-like outer portion 11, and an imperforate portion 12 forming the opposite end, and a portion of the outer side of the ventilator. A baffle plate 13 is fixed within the ventilator and is provided with a shoulder 14 near one end.

The baffle plate is inclined toward the outer surface of the ventilator and the end 45 of the plate is out-turned at 15 for a purpose to be described. The baffle plate 13 is soldered or otherwise secured to the side walls 16 of the ventilator and the lower end is extended to form with the outwardly flanged 55 portions of the sides 16 and end 12 an open

frame work around the ventilator opening 17 in the roof 18. The baffle plate is stiffened by the provision of angle iron members 19, Fig. 3, extending from the shoulder 14 to the out-turned end 15. The lower edge of 60 the casing 10 is out-turned as shown in Fig. 1 to provide a drainage opening 20 adjacent to the shoulder 14.

The lower side of the opening 17 in the roof 18 is covered by a plate or frame 22 having openings 23 therein adapted to be covered by a sliding plate or damper 24 having corresponding openings 25 and provided with a handle 26 by which it may be moved.

Having described the construction of this 70 form of my improved ventilator, the advantages derived from the use thereof will be readily apparent. It is found that the passage of air across a grid-like surface, such as the surface 11, tends to create suction in 75 the grid, withdrawing air through the ventilator from the interior of the car. The path of the air currents from the interior of the car around the baffle plate 13 and out through the grid 11 is clearly indicated by 80 arrows in Fig. 1.

Rain or sleet entering through the grid 11 will be received by the baffle plate 13 and will drain out through the opening 20 without the possibility of entering the car 85 through the roof opening 17. The out-turned end 15 of the plate 13 aids materially in protecting the interior of the car from moisture, and the shoulder 14 serves a similar purpose. The car ventilation may, of course, be easily regulated by suitably positioning the sliding damper plate 24.

In Figs. 5 and 6, I have shown a ventilator of very similar construction applied to a car of the monitor type.

This ventilator includes a grid 30, a baffle plate 31 having an out-turned portion 32, and a continuous curved imperforate end and outer side portion 33, all of these parts being in a general way similar to the 100 corresponding parts of the ventilator shown in Figs. 1 to 4. A sash or window 34 may be provided in place of the slide previously described, the sash being pivoted to swing to open or closed position in the usual way.

The grid 30, being at the lowest part of the ventilator, acts also to provide drainage and renders the special drainage opening unnecessary. The baffle plate 31 is therefore continued to the bottom of the ventilator 110

where it is secured to the slightly inclined bottom plate 35. The path of the air currents is indicated by the arrows and does not differ materially from the circulation 5 in the form previously described.

Having thus described two forms of my invention, it will be evident that changes and modifications can be made therein by those skilled in the art within the spirit and 10 scope of my invention as set forth in the claims and I do not wish to be otherwise limited to the details herein disclosed but what I claim is:—

1. A car ventilator comprising a casing 15 having a gridlike portion and an imperforate portion in its outer face and having an opening in the inner face in part aligned with said grid-like portion, a baffle plate between said grid-like portion and said opening providing an air passage around one end of said plate from the inner to the outer parts of 20 said casing at the imperforate portion and means to control the flow of air through said opening.
25. 2. A car ventilator comprising a substantially rectangular casing having one end of the outer face imperforate and the other end in the form of a rectangular grid, a baffle plate positioned behind the grid and also behind a portion only of said imperforate end

portion, said baffle plate comprising a single inclined plate fixed in said casing and having its upper end out-turned and spaced from the outer face and end wall of the 35 casing.

3. A car ventilator comprising a casing having a part of the outer face formed as a grid, the remainder of the outer face and one end having a continuous rounded imperforate surface, the inner face of said casing 40 having an opening, and a baffle plate interposed between said inner opening and said grid, the plate being inclined and having one end out-turned behind the imperforate part of the outer face.

4. A car ventilator comprising a casing having an outer face with a grid-like end portion, an imperforate baffle plate underlying the whole of said grid-like portion, said plate being formed substantially in a 50 single plane and having an out-turned end spaced from the end of said casing and from the outer face thereof to provide a protected air passage around the end of said plate and within said casing, and stiffening bars fixed to said baffle plate and disposed in the direction of air travel.

In testimony whereof I have hereunto affixed my signature.

CHARLES H. TURNER.
